UNITED STATES PATENT OFFICE

2,257,991

PRICE TAG

Ericsson B. Van Norden, Rainbow Lakes, N. J., assignor to A. Kimball Company, New York, N. Y., a corporation of New York

Application January 27, 1940, Serial No. 315,876

1 Claim. (Cl. 40—25)

This invention relates to price tags and pertains more particularly to tags supplied with attaching pins or staples and commonly referred to as pin tickets.

It is an object of the invention to provide a ticket having an attaching pin or staple so arranged that it may be manipulated, both for attachment and removal, from the side of the merchandise to which the ticket is applied, thus making the ticket available for use on articles such as pillows, for example, which lack a free edge permitting manipulation of the pin from the opposite side.

It is a further object of the invention to provide a covering for the pin in order to prevent the same from engaging and damaging other articles of merchandise.

Other objects and advantages of the invention will appear hereinafter.

A preferred embodiment of the invention selected for purposes of illustration is shown in the accompanying drawing, in which,

Figure 1 is a plan view of the front face of the ticket, showing the manner in which the pin is passed through the merchandise.

Figure 2 is a plan view of the back face of the ticket.

Figure 3 is a view similar to Figure 1, showing the pin bent around the edge of the aperture to secure the ticket to the merchandise.

Figure 4 is a similar view showing the flap passed through the slit.

Figure 5 is a section on the line 5—5 of Figure 4.

Referring to the drawing, the ticket comprises a body portion 1 and a flap 2 separated by a fold line 3. Secured to the body portion is an attaching staple 4 having one short leg or pin 5 passing through the body portion and bent as shown in Figure 2 to hold the staple in place, and having a longer leg or pin 6 passing through the body portion and bent as shown to extend transversely across the ticket substantially parallel thereto. The length of the leg or pin 6 is less than the width of the ticket, and such that the point of the pin 6 is within the marginal outlines of the ticket.

Formed in the body portion opposite the end

of pin 6 is an aperture 7 through which the end of the pin may be passed so that the pin may be bent around the edge of the aperture as shown in Figure 3. Thus, in attaching the ticket to merchandise, the pin 6 is first run through the goods 8. The end of the pin is then passed through the aperture 7 and bent around the edge of the aperture, thus firmly securing the ticket to the goods. The flap 2 is then bent over and the end 10 of the flap may be passed through the slit 9 formed in the body portion, thus covering and protecting the point of pin 6.

A single ticket is shown in the drawing for purposes of illustration, but it will be understood that since the attaching pin is located within the marginal outlines of the ticket, a plurality of such tickets may be made in strip or roll form, and individual tickets may be severed from the strip as required, either by machine or otherwise.

It will be understood that the invention may be variously modified and embodied within the scope of the subjoined claim.

I claim as my invention:

25 A pin ticket comprising a body portion of suitable sheet material, a flap forming an extension of said body portion at one end thereof, but separated therefrom by a fold line, the other end of said body portion terminating in a free edge, said body portion being provided with a slit extending parallel to said fold line and spaced therefrom to receive the end of said flap when folded, an attaching staple permanently secured to said body portion between said fold line and slit, said 30 staple having a single leg extending transversely across said ticket substantially parallel to the rear face thereof and contiguous thereto, said leg terminating in a point within the marginal outlines of the ticket, the distance between said fold line and slit being less than the length of said staple leg, and said body portion being provided with an aperture between said fold line and slit, said aperture being aligned with and opposite said point and extending back from said point 35 a sufficient distance to permit said leg to be manually bent backwards around the edge of said aperture for attaching purposes.

ERICSSON B. VAN NORDEN.
